UNITED STATES PATENT OFFICE.

DAVID A. CUTLER, OF WOLLASTON, MASSACHUSETTS. ASSIGNOR TO ALFRED HALE RUBBER COMPANY, OF ATLANTIC, MASSACHUSETTS, A CORPORATION OF MASSACHUSETTS.

DESIGN FOR A SHOE SOLE OR ANALOGOUS ARTICLE.

Application filed November 5, 1927. Serial No. 24,021. Term of patent 7 years.

To all whom it may concern:

Be it known that I, DAVID A. CUTLER, a citizen of the United States, residing at Wollaston, county of Norfolk, in the State of Massachusetts, have invented a new, original, and ornamental Design for a Shoe Sole or Analogous Article, of which the following is a specification, reference being had to the accompanying drawing, forming a part thereof, in which—

I claim:

The ornamental design for a shoe sole or analogous article, as shown.

This specification signed this 2nd day of Nov. A. D. 1927.

DAVID A. CUTLER.
